STOCKING

Lester C. Laufbahn, Reading, Pa.

Application June 15, 1953, Serial No. 25,482

Term of patent 3½ years

(Cl. D47—7)

To all whom it may concern:

Be it known that I, Lester C. Laufbahn, a citizen of the United States of America, residing at Reading, in the county of Berks and State of Pennsylvania, have invented a new, original, and ornamental Design for a Stocking, of which the following is a specification, reference being had to the accompanying drawing, forming a part thereof.

In the drawing:

I claim:

The ornamental design for a stocking, as shown.
